PHONOGRAPH

John C. Wistrand, New Canaan, Conn., assignor to Columbia Broadcasting System, Inc., New York, N.Y., a corporation of New York

Filed Oct. 20, 1964, Ser. No. 82,255

Claims priority, application Great Britain May 22, 1964

Term of patent 14 years

(Cl. D56—4)

FIG. 1

FIG. 2

FIG. 3

FIGURE 1 is a front elevational view of a phonograph showing my new design;

FIGURE 2 is a perspective view on a reduced scale of the phonograph shown in FIGURE 1 with the lid open and showing one side thereof; and

FIGURE 3 is another perspective view on a reduced scale of the phonograph shown in FIGURE 1 with the lid closed and showing the other side thereof.

The turntable and tone arm partially shown in FIG. 2 are of conventional configuration and appearance.

The rear and bottom of the phonograph (not shown) are conventional.

I claim:

The ornamental design for a phonograph, as shown and described.
